SAFETY RAZOR BLADE SHIELD

Roy S. Pearson, Clarinda, Iowa

Application July 15, 1935, Serial No. 31,397

4 Claims. (Cl. 30—96)

The principal object of this invention is to provide a device that when installed on a safety razor of the Gillette type will protect and shield the razor blade in the razor.

5 A further object of my invention is to provide a blade shield for safety razors that when installed on the razor when not in use will be rigidly secured to the razor and free of any independent movement relative to the razor.

10 A still further object of my invention is to provide a safety razor blade shield that not only successfully protects the delicate edge of the razor blade, but automatically wipes the blade of moisture or other foreign matter at the time of attaching, thereby preventing undesirable rusting of the blade when not in use.

15 A still further object of my invention is to provide an easily detachable or attachable guard shield for safety razor blades that is light in weight, economical in manufacture, and durable in use.

These and other objects will be apparent to those skilled in the art.

20 My invention consists in the construction, arrangement and combination of the various parts of the device, whereby the objects contemplated are attained as hereinafter more fully set forth, pointed out in my claims and illustrated in the accompanying drawing, in which:

25 Fig. 1 is a side view of my device directly after being first loosely assembled on a razor.

30 Fig. 2 is a top plan view of my blade shield installed on a razor.

35 Fig. 3 is an end cross-sectional view of my blade guard taken on line 3—3 of Fig. 1 and shows the position of the various parts of the razor relative to my device before the blade guard shield and razor are rigidly secured together.

40 Fig. 4 is an end cross-sectional view of my device rigidly secured to a razor and in use.

45 Fig. 5 is a perspective view of my safety razor blade shield and more specifically illustrates its construction.

50 Every one who travels knows the desirability of a guard to protect and shield the blade of a safety razor when not in use and which is usually carried loose in the grip or suit case. Although my device is highly desirable for travel usage to thus protect the blade and cuttable items in the carrying case, and to prevent items in the case from becoming soiled by the wet razor blade, the device is also quite desirable for use when at home. The reasons for this are that the blade is 55 protected and preserved against rusting and

against damage by coming into contact with items that might damage the razor blade. Also, my device prevents the accidental cutting of one's self when the razor is not in use.

5 Referring to the drawing, I have used the numeral 10 to designate the head plate of an ordinary safety razor. The numeral 11 designates the guard part of such a razor and the numeral 12 the handle. As is well known, the handle 12 or a part of the handle 12 is threaded onto the 10 shank 13 of the head 12 in order to move the head 10 and guard portion 11 toward or away from each other. The numeral 14 designates the usual razor blade designed to be held between the head 10 and guard portion 11. It is to such a 15 razor that my device is applicable and which I will now describe.

20 I have used the numeral 15 to designate the housing of my blade protective device. This housing is open at both ends and has a longitudinal slot opening 16 extending its entire length and located at its center top. The marginal edges of the housing at this slot 16 are both bent downwardly and inwardly to conform with the longitudinal depressions in the guard 11, respectively, 25 which are just above the outer edge portions of the blade 14 as shown in the drawing. By this construction of the housing a channel chamber in the housing is provided at each side of the longitudinal slot 16. In each of these channels I 30 have mounted a resilient, flexible bar element 17 of suitable material such as cork. These bar elements 17 each have a width less than the top portion of the housing above them, thereby the marginal edge portions of the housing adjacent its 35 slot 16 will overlap or protrude substantially beyond these bar elements, respectively, as shown in Fig. 3.

40 Obviously, any suitable method may be used to hold the bar elements 17 in their respective 40 positions in the housing. In the drawing, I have formed downwardly extending indentations 18 in the top portions of the housing for engaging these elements. In the free face of each of these bar elements 17 I have provided a longitudinal razor blade receiving slit 19. These 45 two slits 19 are directly opposite from each other and are designed to receive the two cutting edge portions of a razor blade 14, as shown in the drawing. They are so designed that when not 50 engaging a razor blade they tend to completely close.

55 The practical operation of the device is as follows: With the razor in loose condition, that 55

is, with the handle rotated to a position where the head 10 and guard 11 are out of engagement with each other and the razor blade in a loose condition between them, as shown in Fig. 3, the 5 razor and its blade are slid longitudinally into my shield with the head 10 inside the housing slidably engaging the inside bottom of the housing and the guard portion 11 above the housing. The razor is thus moved until it assumes a position such as shown in Fig. 3. During this 10 operation the cutting edge portions of the razor blade will automatically slide into and engage the two slit openings 19 of the resilient bar elements 17, as shown in the drawing. These slit openings 19 are mere cuts in the bar elements and therefore this sliding of the blade into them will wipe the blade of all moisture and foreign matter. As these bar elements are of cork or like 15 they will readily absorb any moisture from the blade and will not harm or damage the cutting edges of the blade. The bar elements 17 are so spaced apart that the head 10 of the razor will loosely rest between them and under the razor blade.

20 25 The slits 19 in the cork elements 17 are of such height from the bottom of the housing and in such positions relative to the marginal edge portions of the housing adjacent the slot 16, that the top of the blade will be closely adjacent for 30 engagement with the marginal edge portions of the housing, which as we have seen, are bent downwardly and inwardly to conform with the curvatures of the guard 11 and to engage the top of the razor blade as shown in the drawing. After 35 the razor and its blade have thus been placed in my device it is merely necessary to tighten the razor by rotating the handle in the same manner as when it is desired to tighten the blade in the razor for shaving purposes. This 40 tightening of the handle of the razor will bring the head and guard closer together, but the razor blade will not be flexed such as is the ordinary case when it is desired to tighten the razor to shave. The reason for this is that the 45 top of the blade will be drawn tightly upwardly against the downwardly and inwardly extending marginal edge portions of the housing adjacent the slot opening 16 and the guard portion of the 50 razor will be drawn downwardly onto these upper portions of the housing, as shown in Fig. 4, thereby rigidly securing the razor and its blade to my device and against accidental removal or displacement. To all intents and purposes, my 55 shield becomes a rigid part of the tightened razor when not in use. In other words, the safety razor is first assembled to my device in a loose condi-

tion and then tightened. To remove the razor from my protective shield it is merely necessary to loosen the razor by rotating the handle in the opposite direction and sliding the razor longitudinally out of and from the device. The removal and insertion of the razor is facilitated by rounding the corners of the upper portion of the housing adjacent the slot 16, as shown in 5 Fig. 5. Obviously, due to this and the downwardly and inwardly extending marginal edge 10 portions of the housing adjacent the slot opening, the razor will be guided into its place in the device and out of the device and the razor blade will fall into line with the slits 19 without much attention from the operator.

15 One of the important features of my device is that during the insertion of the razor and even after the razor has been tightened, the razor blade will be maintained in a straight, flat condition.

20 Some changes may be made in the construction and arrangement of my improved safety razor blade shield without departing from the real spirit and purpose of my invention, and it is my intention to cover by my claims any 25 modified forms of structure or use of mechanical equivalents which may be reasonably included within their scope.

I claim:

1. In a safety razor and blade shield, a housing having a slot opening, and a bar of cork inside said housing having a slit opening designed to receive the blade of the razor to be held.
2. In a safety razor and blade shield, a housing having a slot opening, and two spaced apart 35 elements of resilient material inside said housing each having a longitudinal razor blade slit opening designed to receive one of the cutting edge portions of a safety razor blade.
3. In a device of the class described, a housing 40 having a slot; said housing having its marginal edge portions adjacent said slot designed to extend between the guard portion of a safety razor and a double-edged safety razor blade, and two spaced apart resilient elements inside said housing designed to engage the cutting edge portions 45 of said razor blade.
4. In a device of the class described, a housing open at both ends and having a centrally located side slot opening extending its entire length, 50 downwardly and inwardly extending flanges adjacent said slot opening, and two slotted cork bars spaced apart from each other and positioned at each side of said slot opening respectively.

55 ROY S. PEARSON.
